United States Patent Office.

FRANCIS ZELL, OF LOUISVILLE, KENTUCKY.

Letters Patent No. 79,047, dated June 16, 1868.

IMPROVEMENT IN SHUTTER-FASTENING.

The Schedule referred to in these Letters Patent and making part of the same.

TO ALL WHOM IT MAY CONCERN:

Be it known that I, FRANCIS ZELL, of Louisville, in the county of Jefferson, and State of Kentucky, have invented a new and useful Shutter-Fastening; and I do hereby declare the following to be a full, clear, and exact description of the same, sufficient to enable others skilled in the art to which my invention appertains to fully understand and use the same; reference being had to the accompanying drawings, which are made part of this specification, and in which—

Figure 1 is a sectional view of a fragment of a window-shutter and frame, with my invention applied.

Figure 2 is a view of a portion of the inner side of the shutter.

Figures 3, 4, 5, 6, and 7 are detached views of the several parts pertaining to the fastening-device.

Similar letters of reference indicate corresponding parts in the several figures.

This invention is more particularly designed to supersede the thumb-screws which are almost universally employed to fasten the shutters of store-windows, and which are objectionable on account of the many turns which are required in order to screw them up to the fastening-point, and the consequent consumption of time in performing the operation. The thumb-screws are also objectionable on account of their liability to get out of their sockets and be lost.

My device requires but a partial rotation, a single turn by the thumb and finger sufficing to secure the shutter, and the fastening-device is permanently retained in the frame, so as to be always ready for service.

In the drawing, fig. 1, A may represent a fragment, the lower part of a window-frame, and B a fragment of the shutter. The fastening-device, which secures the shutter B to the frame A, is shown detached in fig. 5. It is designed to be cast of a single piece, and consists of successive cylindrical portions, C¹ C², to which is joined the flattened thumb-piece C³, by which the device is turned upon its axis, after the manner of the ordinary thumb-screw. Unlike the thumb-screw, it is devoid of threads, and depends, as a fastening, upon its shouldered head C⁴, which, permanently projecting outside of the window-frame, enters the recess b when the shutter is put up, and requires but a partial turn to then engage with the shoulders or ledges at b' b', and secure the shutter.

The socket or aperture to accommodate the enlarged portion C¹ is first bored in the window-frame A, and the two slotted and matched plates D D (see figs. 6 and 7) are then applied to the shank C from opposite directions, and screwed to the frame A, so as to prevent the displacement of the fastening-device by an outward or an inward movement. Hence the fastening-device is not liable to be casually drawn or pushed out.

The plates D D may be provided with corresponding straight-sided slots, and may present perfectly flat and unbroken plane surfaces on both sides; but I prefer to construct each plate as shown in the drawings, that is to say, with the sides of the slot diverging toward the centre of the plate, and with a corresponding projection or raised portion, d. When the plates are put together, the projection d of one plate occupies so much of the slot of the other plate as does not assist in forming the hole which accommodates the shank C of the fastening-device, as shown in fig. 4.

The provision of the tapering projections d not only enables a neater and more solid finish, by filling the space which would be otherwise left in each plate, but prevents said plates from moving in any direction upon each other. Thus the projections d serve as an important adjunct of the screws at h, and, in fact, are much more effective than the latter in coupling and locking the plates D together. This construction of the plates D is the more to be desired on account of the tendency to their derangement which would otherwise be exerted by the stop-pin e, which, projecting from the fastening-device, has its play limited between the shoulders d' d' on the respective plates D D, and which serves to determine and indicate the extent of rotation which is necessary to engage the fastening-device with the shutter.

The plates D D, constructed as above described, will be found a very desirable means of retaining in place the ordinary shutter-fastening thumb-screws, and I propose to employ them for this purpose.

The head, C⁴, may be of any form other than that represented, it being only essential that it have shoulders to engage with corresponding shoulders or ledges in the shutter.

I propose to employ this fastening for any purpose to which it may be applicable as a fastening-device. Having thus described my invention, what I claim as new herein, and desire to secure by Letters Patent, is—
1. The fastening-device, consisting of the successive cylindrical portions C C¹ C², the thumb-piece C³, and shouldered head C⁴, in combination with two matched retaining-plates, substantially as and for the purpose set forth.

2. The plates D-D, constructed with slots having diverging sides, and with corresponding projections d d, substantially as and for the purpose set forth.

To the above specification of my improved shutter-fastening, I have signed my name, this thirtieth day of April, 1868.

FRANCIS ZELL.
